UNITED STATES PATENT OFFICE.

ERNEST B. WILKINS, OF HELENA, ARKANSAS.

DISPLAY CASE OR TRAY.

Application filed August 21, 1928. Serial No. 301,023.

This invention relates to an improved type of display tray designed especially for use in stores, and has for its primary object to provide a structure in which the article carrying receptacle forms a movable top adapted to be used in horizontal position or adjusted to an inclined position when necessary for the better display of articles contained therein.

Another object of the invention is to provide a store fixture of the above described character wherein the article carrying tray may be inverted to provide a table, the bottom of the tray forming the table top.

A further object of the invention is to provide a display fixture for use in any place where material is to be demonstrated, which will be of strong and durable construction, and comparatively inexpensive to manufacture and set up.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a perspective view of the tray supporting frame of the display device;

Figure 2 is a transverse sectional view of the structure showing the tray in tilted position;

Figure 3 is a transverse sectional view of the upper portion of a modified form of the fixture;

Figure 4 is a perspective view of a modified form of the structure shown in Figures 1 and 2, showing a slat tray substituted for the walled tray;

Figure 5 is a transverse sectional view of the upper portion of Figure 4;

Figure 6 is a sectional view taken upon the line 6—6 of Figure 5.

The display stand embodying the present invention comprises a number of upright supports or legs 1, 2, 3 and 4 arranged in vertical position to form a rectangle, the legs 1 and 4 and 2 and 3 making up two pairs, each pair being connected by a lower cross bar 5 which bars are in turn connected by a longitudinally extending base strip 6.

The upper ends of the legs are each cut away upon the inner face to receive the ends of the end panels 7, which panels connect the ends of each pair of legs as shown and connecting the legs 1 and 2 at the front of the structure is an apron strip 8, the top edge of which is arranged adjacent to the lower edges of the end panels 7 as shown.

A back strip 9 of materially greater height than the panels 7 and apron 8, connects the rear legs 3 and 4, the lower edge of this strip being substantially in the same plane as the lower edges of the end panels 7 while the top edge extends a slight distance above the top edges of the end panels.

Each of the end panels 7 has extending along the inner face thereof adjacent the lower edge, the tray supporting strip 10, the front ends of these strips being beveled as at 11 to form the forwardly and downwardly inclined supporting surface as shown, this surface terminating against the inner face of the apron 8.

Designed to be positioned upon the supporting strips 10 between the end panels 7 is a display tray 12, the width of which is equal to the width of the stand or in other words, when the tray is in position with the back wall abutting the strip 9, the front wall thereof overlies and is flush with the front face of the apron 8.

When it is desired to position the tray 12 at an inclination for the better display of the contents thereof, the back of the tray is lifted and the entire tray structure is then moved backwardly until the lower front edge drops on to the inclined forward ends of the supporting strips 10. The back of the tray will then be resting upon the top edge of the strip 9 while the front, resting upon the inclined surfaces 11 of the strips 10 will bear against the rear top edge of the apron 8 as shown in Figure 2.

In addition to using the tray 12 as a receptacle or container for goods on display, it may be inverted and placed in position between the end panels 7, resting upon the strips 10 and the top edge of the apron 8, so that the bottom thereof lying flush with the top edges of the end panels 7 may be employed as a table surface.

A slight modification of the structure just described is shown in Figure 3. In this form the stand structure is substantially the same with the exception of the tray supporting strip. This strip is divided forming the rear

part 13 and the forward part 14, the adjacent ends thereof being in spaced relation and oppositely bevelled, the forward end of the portion 13 having the relatively long 5 bevel 15 while the adjacent end of the portion 14 has the slight or sharp bevel 16. In this form also the front apron 17 instead of being arranged with the top edge thereof in the same plane as the top edge of the tray supporting strips, has its top edge in substantially the same plane as the top edges of the end panels 18 so that the tray 19 when in horizontal position is entirely inclosed on its four sides. When it is desired to arrange 10 the tray in an inclined position the rear is elevated and the entire structure moved backwardly until the forward lower edge of the tray drops between the opposed ends of the strip sections 13 and 14 at which time the 15 back part of the tray will be in position to be supported upon the back strip 20 of the stand structure. Owing to the inclination of the faces of the opposed ends of the portions 13 and 14 the tray will be securely held 20 against movement.

From the foregoing description, it will be readily seen that the herein described structure is of simple design but may be advantageously employed in various capacities for 25 the display of merchandise as for example in groceries, drug stores, dry-goods stores and the like.

For the purpose of displaying vegetables and like commodities which ordinarily carry 30 more or less dirt and sand such as kale, spinach, potatoes, etc., there is provided to be substituted for the tray structures 12 and 15 a flat slat platform indicated as a whole by the numeral 21. This platform comprises a series of spaced parallel slat members 22 connected across their ends by the cross cleats 23. The cross cleats 23 are secured to the slats 22 inwardly of the ends thereof so as to permit the platform to be placed within the upper 40 portion of the frame structure in substitution for the tray 12, the ends of the slats resting upon the strips 10 which normally support the tray 12 in the manner shown.

It is obvious that the platform may be arranged in the tilted position in which the tray 45 12 is shown in Figure 2, if desired, the forward one of the slats 22 positioning at its ends against the inclined end faces 11 of the strips 10.

Having described my invention what I claim is:—

1. An article of the character described,

comprising a supporting structure including supporting legs, a frame carried by said legs comprising end panels, a front apron connecting the panels and a back strip connecting the panels, supporting strips carried by said end panels at the lower edges of the inner faces thereof, a tray arranged within the frame and supported upon said strips, and means for supporting said tray at an inclination upon the strips, said means comprising an inclined surface formed on each of said strips adjacent the front end thereof, upon which surfaces the tray is designed to position with the back thereof resting upon said back strip. 60

2. An article of the character described, comprising a supporting structure including supporting legs, a frame carried by said legs comprising end panels, a front apron connecting the panels and a back strip connecting the panels, supporting strips carried by said end panels at the lower edges of the inner faces thereof, a tray arranged within the frame and supported upon said strips, and means for supporting said tray at an inclination upon the strips, said means comprising an inclined surface formed on each of said strips adjacent the front end thereof, upon which surfaces the tray is designed to position with the back thereof resting upon said back strip, said apron being arranged in a plane below the end panels and the back strip and having the forward lower edge of the tray abutting 70 against the rear face thereof when the tray is in an inclined position. 80

3. In an article of the character described comprising a supporting structure consisting of a frame having end panels, a back strip 90 connecting the panels, supporting strips carried by said end panels at the lower edges of the inner faces thereof, a tray adapted to be normally horizontally arranged within the frame and supported upon said strips, means 95 for supporting said tray at an inclination upon said strips comprising an inclined surface formed on each of said strips adjacent the front end thereof upon which surface the tray is designed to position with the back 100 thereof resting upon said back strip, and an abutment adjacent the inclined surface of said tray supporting strips, against which the forward lower edge of the tray may bear 105 when the tray is in inclined position. 110

In testimony whereof I hereunto affix my signature.

ERNEST B. WILKINS.
